UNITED STATES PATENT OFFICE.

JOSEPH S. MORRISON, OF WALLPORT, OREGON.

ORE-SEPARATOR.

1,227,552.

Specification of Letters Patent.

Patented May 22, 1917.

Application filed September 9, 1915. Serial No. 49,831.

To all whom it may concern:

Be it known that I, JOSEPH S. MORRISON, a citizen of the United States, and resident of Wallport, county of Lincoln, State of Oregon, have invented a new and useful Improvement in Ore-Separators, of which the following is a specification.

This invention relates to magnetic devices which are used for separating iron ore from sand. As is well known, iron, gold and other precious metals in the free state, are often mixed with sand and the operation of separating the ore from the sand is very difficult.

Owing to the fact that a magnet will exert an attractive force on the iron and not on the other elements in mixture therewith, certain magnetic devices have been used in which the sand is brought into contact with a magnetic pulley. The iron will be magnetically held by the pulley while the remaining material will not, and in this way a separation will be procured. These devices however, have not proven entirely satisfactory owing to the fact that the iron will stick to the pulley and other devices must be used for collecting it therefrom. Furthermore, it is impossible to bring all of the material in direct contact with the pulley, with the result that a great deal of the iron is lost, and the collected iron will also contain a high percentage of other materials.

One of the main objects of this present invention is to provide an improved magnetic separating device in which the iron will not come in direct contact at any time with the magnet, and therefore, when it is carried beyond the zone of magnetic influence, it may be easily collected.

Another of the main objects of this invention is to provide means for feeding the sand to the magnetic separator which will so operate as to cause every particle of material to be brought into the zone of strongest magnetic attraction so that every particle of the iron will be separated from the sand.

All of the features of my invention are fully shown in the accompanying drawing, in which,

The figure is a longitudinal, vertical section of my device.

In this drawing, *a* represents the longitudinal members of the bed upon which the separator is mounted, and *b* are transverse

members. Said bed may be mounted on a vehicle and thus be capable of transportation from place to place or it may be stationary and the material hauled to it. Vertical members *c* are mounted on the longitudinal members *a*, on opposite sides of the bed.

A transverse shaft *d* is journaled between the upper ends of the vertical members *c*, and has fixed on its outer end a pulley *e*, and a sprocket *f*. Journaled between the longitudinal members *a* is a transverse shaft *g*, parallel with the shaft *d*, and located in the same vertical plane. A third transverse shaft *h* is journaled in bearings *i* which are mounted on the longitudinal members *a*. Fixed on the shafts *d*, *g*, and *h* respectively, are the pulleys *d'*, *g'* and *h'*, and an endless carrier *j*, runs over the pulleys *d'*, *g'* and *h'* in the direction indicated by the arrow. A prime mover *k*, of the vertical gas-engine type, transmits rotation to the pulley *e*, and thus to the carrier *j*, by a belt-drive *k'*.

An electro-magnet *l* is rigidly mounted on brackets *m*, in the position shown in the drawing, said magnet being in the circuit of the electric conductors *n* and *o*. A dynamo *p* which energizes said circuit, is driven by a belt *q* from the prime mover *k*, and in this way, the attractive force of the magnet is maintained. A current-controlling device is indicated by the rheostat *r*, and a switch by *r'*. It will be noted that the face of the magnet is located adjacent the inner side of the vertical portion of the endless carrier *j*. A series of inclined baffle-plates *s* are supported between the vertical members *c*, so that their lowermost ends are spaced slightly from the outer face of the vertical portion of the endless carrier *j*.

A bottomless hopper *t* is located above the baffle-plates *s*, and is adapted to discharge directly upon the uppermost of said plates. A hopper *u* is located adjacent the bed of the device, said hopper *u* being made with an open bottom. Pulleys *v* and *w* are fixed on the transverse shafts *v'* and *w'* these latter being journaled in the positions shown in the drawing. A sprocket *v²* is fixed on the shaft *v'* and a chain drive *x* connects the sprockets *v²* and *f*. An endless conveyer *y* runs over the pulleys *v* and *w*, and is provided with elevating members *y'* which carry the material upward from the hopper and discharge it into the hopper *t*. Located beneath the pulley *h'* is a delivery chute *z*.

or other suitable receptacle into which the iron is deposited from the endless carrier *j* as the latter runs over the pulley *h*.

The general operation of my device is as follows: The sand containing the iron to be separated is delivered to the hopper *u*, and is elevated therefrom to the hopper *t*, by the conveyer *y*. The sand then drops by gravity upon the baffle-plates *s*, and is deflected by them so as to be thrown against the outer side of the upwardly moving endless carrier *j*. The magnetic attraction of the electro-magnet *l* will cause the particles of iron to adhere to the carrier *j* until they have been carried beyond the zone of magnetic influence, while the remaining portion of the sand will drop freely away from the carrier. As the carrier runs over the pulley *j'*, which is located outside of the zone of magnetic attraction, the particles of iron will be delivered by gravity into the receiver *z*.

The series of baffle-plates *s* are arranged one above the other spaced apart, and each is inclined toward the carrier *j*, the lower edges of the baffle-plates terminating in close proximity to said carrier. When the sand drops downward over the inner edge of the topmost baffle-plate and along the carrier *j*, part of the iron particles of the sand will be attracted and carried away by the carrier. The rest of the sand will be interrupted in its fall by the inner edge of the next baffle-plate, whereupon this body of sand will be broken up and sent against the carrier for further iron extraction. The same process will continue at each consecutive baffle-plate. By increasing the number

of baffle-plates the speed of travel of the sand downward along the face of the carrier can be retarded to any average rate of fall desired. In this way every particle of iron will be extracted by the carrier, the remaining portion of the sand being discharged from the bottom of the device.

I claim:

1. In a device of the character described, the combination of a hopper, a housing located under the hopper, a vertically stacked series of baffle plates spaced apart in said housing, an endless carrier-belt having a portion disposed to extend vertically along the inner edges of said stack of baffle plates, the latter being inclined so as to discharge against said vertical portion of the belt, an electromagnet located adjacent the inner side of said vertical portion of said belt, means for energizing the electromagnet, and means for driving said belt, so arranged as to cause said vertical portion of the belt to travel upward.

2. In a device of the character described, the combination of a vertically stacked series of baffle plates spaced apart, an endless carrier-belt having a portion disposed to extend vertically along the inner edges of said stack of baffle plates, the latter being inclined so as to discharge against said vertical portion of the belt, an electromagnet located adjacent the inner side of said vertical portion of said belt, means for energizing the electromagnet, and means for driving said belt, so arranged as to cause said vertical portion of the belt to travel upward.

JOSEPH S. MORRISON.
